MEANS FOR DEICING PROPELLER SPINNERS

Howard M. McCoy, Patterson Field, Ohio

Application May 11, 1943, Serial No. 486,501

6 Claims. (Cl. 244—134)

(Granted under the act of March 3, 1883, as amended April 30, 1928; 370 O. G. 757)

The invention described herein may be manufactured and used by or for Government for governmental purposes, without the payment to me of any royalty thereon.

This invention relates to improvements in means for preventing the formation of ice on airplane propeller spinners.

The problem of icing on airplanes has always been a serious one and with severe icing conditions prevailing up to 25,000 ft., well below the operating ceiling of modern aircraft, and with military demands consistently requiring flights under hazardous weather conditions, the problem is one of first rate importance. To prevent icing of airplane wings, rubber boots are installed on the leading edges and by means of air pressure alternately applied and relieved such boots are inflated and deflated to crack and break up the ice so that the airstream will carry it away. At this time propeller blades are usually protected against icing by anti-icing fluid continuously applied while icing conditions obtain. Ice formation on propeller hubs and pitch control mechanisms is inhibited by rubber covered spinners. Because of the increase in size of spinners and their slower speeds due to the use of reduction gearing there is more need than heretofore for apparatus which will prevent ice from forming on spinners.

Objects of the present invention are to provide reliable apparatus for preventing ice formation on propeller spinners which does not materially increase the weight of the airplane, which requires little power for operation, which may be installed in existing types of airplanes without interference with other apparatus and which does not affect the performance of the airplane. A specific object is to provide apparatus of the character indicated whose cycle or rate of movement may be controlled by the pilot or other operator. Other objects will appear from the following description of a preferred embodiment of the invention shown in the accompanying drawing.

In said drawing:

Fig. 1 is a sectional elevation, more or less diagrammatic, of a propeller spinner with the apparatus for de-icing installed;

Fig. 2 is a section on line 2—2 of Fig. 1; and

Fig. 3 is a diagram of the apparatus.

Referring particularly to the drawing, a propeller spinner 5 has two reinforcing diaphragms 6, 7 between which the propeller hub (not shown) is mounted. An annular bearing support 8 is

secured to or is integral with diaphragm 7 and is co-axial with the propeller shaft (not shown). Mounted on annular support 8 is a ring gear 9 and ball bearings 10 are provided to allow said gear to rotate relative to its support or to be stationary while the support rotates with the propeller. In other words gear 9 is a free floating gear. To govern rotation of gear 9, a brake 11, which may be hydraulic, electrical or mechanical, is mounted on the engine nose 12 or other stationary structure, and is controlled by a conventional control 11a accessible to the pilot. Brake 11 has a shaft 13 and a pinion 14 meshing with gear 9. A rotary air pump 15 is mounted on diaphragm 7 and is driven by a shaft 16 carrying pinion 17 meshing with gear 9. A rotary distributor valve 18 is also secured to diaphragm 7 and is driven by pinion 19 meshing with gear 9. It will be clear that as the air pump and distributor valve revolve with the propeller about its axis, the reactions from their pinions on the ring gear 9 cause the latter to rotate on bearings 10. But when the ring gear is braked both the air pump and the distributor valve will be driven at a speed proportional to the degree of braking, i. e., the greater the braking effort, the higher the speed of the pump, etc.

Secured to the outside of the spinner 5 are one or more inflatable annular cells 20, 21, 22, each 30 preferably composed of rubber, each cell being sealed to the atmosphere and closed to the other cells, so that it may be inflated and deflated independently. A flexible cover 24, which may be of textile material or rubber, encloses the three 35 cells and is secured by conventional means (not shown) to the outside of the spinner. In Fig. 1 cell 20 is deflated, cell 21 is inflated and cell 22 is deflated, while the dot and dash lines indicate the inflation of cells 20 and 22 respectively. The 40 compressed air is conducted from the pump through a tube 25 to the distributor valve. As the distributor valve is rotated compressed air under pressure of 7 to 10 lbs. per sq. in. is conducted through tubes 26, 27, 28 to the cells in sequence and is exhausted from them sequentially, the exhausts flowing back through tubes 26, 27 and 28 to the distributor valve and out through exhaust pipe 29 leading to the air pump. As pipe 50 29 is a low pressure line it is indicated in dotted lines, while the high pressure side of the system is shown in full lines.

The preferred system also includes a pressure relief valve 30, a check valve 31, and an air filter 32 having another pressure relief valve 33 (for

discharge of excess air and moisture). All these parts, plus the air pump, distributor valve and tubing, must be balanced statically and dynamically, since the entire system (except the brake) rotates with the spinner.

Obviously the invention is not restricted to the particular mechanism herein shown by way of illustration but may assume various forms neither shown nor described.

What I claim is:

1. De-icing apparatus for propeller spinners comprising, in combination, one or more inflatable and deflatable cells mounted on the outside of the spinner to rotate therewith; a pump driven by power derived from the act of propeller rotation; tubes connecting the pump to the cells to inflate them; means to control discharge of the compressed air in the cells; and operator-controlled means to control the pump and the discharge-controlling means and the speed of operation thereof. 20

2. The invention according to claim 1, wherein the operator-controlled means comprises a brake having a pinion meshing with a free floating ring gear; said ring gear surrounding the propeller shaft; the pump having a pinion also meshing with the ring gear to rotate the latter synchronously with the propeller, except when the brake restrains such rotation to operate the pump and the discharge-controlling means to 30 inflate and deflate said cells.

3. In combination with a propeller spinner, a flexible envelope surrounding and fixed to the spinner; a pump on the inside of and rotating with the spinner and adapted to deliver compressed air to the envelope; intermittently acting means to discharge air from the envelope so that deflation follows inflation at regular intervals; means supported inside the spinner to drive the pump; the last named means normally rotating with the pump; and an operator-controlled brake engaging the last named means to slow up or stop rotation of the same, thereby to operate the pump at variable speeds. 40

4. In combination with a propeller spinner, an inflatable envelope on the outside of and fixed to the spinner; means for forcing air into the envelope; means for discharging air from inside the envelope; and mechanism operated by power

derived from the rotating spinner and controlled by the operator to vary the speed of operation of both of said means and to stop both of said means.

5. De-icing apparatus for airplane propeller spinners comprising, in combination, an inflatable envelope adapted to be secured on the outside of the spinner; a ring gear carried on the inside of the spinner and rotatable independently of the spinner about the axis thereof; a rotary valve fixed inside the spinner to rotate about the spinner axis; a pinion on the rotary valve meshing with the ring gear; a rotary air pump fixed inside the spinner to rotate therewith; a pinion on the air pump meshing with the ring gear; a tube connecting the output side of the air pump with the rotary valve; another tube connecting the rotary valve with the interior of the inflatable envelope; so that compressed air from the pump is led through the valve to the envelope; said rotary valve effecting alternate inflation and deflation of the envelope; the ring gear, valve, pump and connecting tubes all being balanced statically and dynamically so as to be capable of rotation at the same speed as the propeller; and an operator-controlled brake fixed to a stationary part of the airplane and having a pinion also meshing with the ring gear, said brake providing means to retard or stop rotation of the ring gear, thereby to cause said valve and pump to operate at speeds variable proportionately to the amount of retardation. 15

6. De-icing apparatus for propeller spinners comprising, in combination, one or more inflatable cells, each toroidal in form adapted to be secured upon the outside of a spinner; means for forcing air into the cells in regular sequence beginning with the cell nearest the nose of the spinner; means for discharging compressed air from the cells in the same sequence; both of said means being driven by power derived from rotation of the spinner; and means to control the speed of operation of both of said means; the entire apparatus except the control means being balanced dynamically and statically so as to be capable of rotating at the same speed as the propeller. 35 40 45
